Chas. F. Lewis,
Inventor,

UNITED STATES PATENT OFFICE.

CHARLES F. LEWIS, OF NEW YORK, N. Y.

ELECTRIC SWITCH.

964,798.

Specification of Letters Patent. Patented July 19, 1910.

Application filed May 31, 1908. Serial No. 319,528.

To all whom it may concern:

Be it known that I, CHARLES F. LEWIS, citizen of the United States, and resident of the city of New York, in the county of New York and State of New York, have invented certain new and useful Improvements in Electric Switches, of which the following is a specification.

This invention relates to electric switches, but more particularly to that class of electric switches in which it is desirable to obtain a quick breaking of the points of contact. To accomplish this in a simple and efficient manner in my invention, I prefer to employ an insulated base, upon which may be mounted, in suitable bearings, a movable rod or shaft which may form a support for a contact member or members, and parts operatively connected therewith. Said contact member may consist of a piece of conducting material of suitable shape, loosely mounted upon said rod by means of a suitable bushing which may be of an insulating material. In the operation of said contact member, I prefer to use suitable springs for producing pressure upon the contact member. A second contact member may be used with the aforesaid member and a pair of suitable springs may be provided which operate the contact device upon the supporting rod or shaft. Said pair of contact springs may bear upon aforesaid contact member to produce a resistance to the motion thereof.

The details of construction of an embodiment of my invention are shown in the accompanying drawings. Like parts are designated by like figures of reference.

Figure 1 is a plan view of a single pole switch. Fig. 2 is a plan view of the same, partly in cross section. Fig. 3 is a plan view of a modification, showing the invention as applied to a double pole switch. Fig. 4 is a plan view similar to Fig. 3, partly in section.

Figure 1 is a base of insulating material represented by 1, upon which a rod or shaft 2 may be slidably mounted in suitable bearings 3 and 4. Upon said rod or shaft 2 may be mounted a contact member 5 of suitable conducting material, which, when the switch is closed is in contact with the spring contacts 6 and 7. Said pair of springs are electrically in connection with the binding posts 8 and 9. Compression springs 10 and 11 may be mounted upon said rod or shaft 2, in an abutting relation to stop-collars 12 and

13 suitably mounted upon and attached to said rod or shaft 2. Said stop-collar 13 may be provided with a suitable insulating buffer 14 which engages the contact member 5. Said rod or shaft 2 may be provided with suitable terminals or beads 15 and 16 which are intended to act as a check to the longitudinal motion thereof. The said contact member 5 may be provided with a bushing 65 of suitable insulating material 17.

In the modification of my invention as represented in Figs. 3 and 4, 21 represents a base of suitable insulating material, upon which may be mounted a rod or shaft 22 in suitable bearings 23 and 24. A contact member of suitable conducting material 25 may be loosely mounted upon said rod or shaft 22, which, when the switch is closed, forms an electrical connection with binding posts, such as 28 and 29. In this modification of my invention, I prefer to employ suitable springs 30 and 31 to produce pressure upon desirable points. Said springs 30 and 31 may be mounted upon said rod or shaft 22 in an abutting relation to suitable stop-collars 32 and 33 attached thereto. Said stop-collar 33 and rod or shaft 22 may be provided with suitable insulating material as represented by 34 and 35. A second pair of contact members 36 and 37 may be suitably mounted upon said base 21 and electrically connected with binding post such as 38 and 39. A second contact member 43 of suitable conducting material may be mounted upon said rod or shaft 22 and insulated from said contact member 25 by suitable insulating material as represented by 40. When the switch is closed said contact members form separate electrical connections between said pairs of contact springs or members. Said rod or shaft may be provided with suitable terminals or beads 41 and 42, which are intended to act as a check upon the longitudinal motion thereof.

In the operation of the preceding embodiment of my invention shown in Figs. 1 and 2, the rod or shaft 15 is pressed inwardly until it attains the position as represented by Fig. 2. This motion of the rod or shaft 15 compresses the springs 10 and 11 and upon any further inward motion the pressure of the spring 10 upon the contact member 5 overcomes the retaining influence of the springs or contact members 6 and 7, and said member 5 is quickly withdrawn from them. This

motion produces the desired quick break of the current passing through the members 5, 6 and 7 respectively. The position of the foregoing members is shown in the accompanying drawings by the dotted lines in Fig. 1. When the rod 15 is released the spring 11 returns the members to their original position and the circuit is closed again.

The operation of the double pole switch 10 as shown in the modification of my invention in Figs. 3 and 4 is similar to that just described. The inward movement of the rod 22, which may be caused by any desired means engaging the end 41 thereof, 15 compresses the spring 30 between the collar 32, which is fixed to the rod 22, and the sliding contact member 25. When the pressure against the contact member 25 is great enough to overcome the contact springs 26, 20 27, 36 and 37, the contact members 25 and 35, which move together on the rod 22 but are insulated therefrom and from each other, move quickly to the position indicated by the dotted outline in Fig. 3, thus breaking 25 both circuits simultaneously.

It will be seen that the operation of the device is the same whether a single or double pole is used and both constructions are described for the purpose merely of showing 30 the adaptability of my invention to various constructions and uses.

As many changes could be made in the above construction and many apparently widely different embodiments of my invention 35 designed without departing from the scope thereof, I intend that all matter contained in the above description or shown in the accompanying drawings shall be interpreted as illustrative merely of an operative 40 embodiment of my invention and not in a limiting sense.

What I claim is:

1. In a switch, in combination, a sliding rod, a contact member slidably mounted on 45 said rod, a stop positioned on said rod to limit the movement of said contact member in one direction, a second stop positioned on said rod, a spring positioned between said second stop and said contact member and 50 adapted to be compressed when said rod and stop are moved relative to said contact member, and a pair of fixed spring contacts adapted to grip and hold said sliding contact member in engagement therewith while 55 said rod is moved until the pressure of the compressed spring overcomes the grip of said spring contacts, causing said sliding contact member to move with accelerated speed out of engagement therewith and 60 against said first named stop.

2. In a switch, in combination, a sliding rod, a contact member slidably mounted on said rod, a cylindrical stop positioned on

said rod to limit the movement of said contact member in one direction, a second stop 65 positioned on said rod, a spring positioned between said second stop and said contact member and adapted to be compressed when said rod and stop are moved relative to said contact member, and a pair of fixed spring contacts positioned on opposite sides of said contact member and adapted to grip and hold said sliding contact member in engagement therewith while said rod is moved until the pressure of the compressed spring overcomes 70 the grip of said spring contacts, causing said sliding contact member to move with accelerated speed out of engagement therewith and against said first named stop.

3. In a switch, in combination, a sliding rod, a conducting contact member slidably and insulatedly mounted on said rod, a stop positioned on said rod to limit the movement of said contact member in one direction, a second stop positioned on said rod, a 80 spring positioned between said second stop and said contact member and adapted to be compressed when said rod and stop are moved relative to said contact member, and a pair of conducting fixed spring contacts 85 adapted to grip and hold said sliding contact member in engagement therewith while said rod is moved until the pressure of the compressed spring overcomes the grip of said spring contacts, causing said sliding contact member to move with accelerated speed out of engagement therewith and 90 against said first named stop opening the circuit through said switch.

4. In a switch, in combination, a sliding rod, a pair of conducting contact members slidably mounted on said rod and insulated therefrom and from each other, a stop positioned on said rod to limit the movement of said contact members in one direction, a second stop positioned on said rod, a spring positioned between said second stop and said contact members and adapted to be compressed when said rod and stop are moved relative to said contact members, and a plurality of pairs of fixed spring contacts 105 adapted to grip and hold said sliding contact members in engagement therewith while said rod is moved until the pressure of the compressed spring overcomes the grip of 110 said spring contacts, causing said sliding contact members to move with accelerated speed out of engagement therewith and against said first named stop.

Signed at the city of New York in the 120 county of New York and State of New York this 28th day of May A. D. 1906.

CHARLES F. LEWIS.
